UNITED STATES PATENT OFFICE.

EDWARD J. BIRKETT, OF RACINE, WISCONSIN, ASSIGNOR TO J. I. CASE THRESHING MACHINE COMPANY, OF RACINE, WISCONSIN, A CORPORATION.

EXCAVATING AND LOADING MACHINE.

1,287,195.

Specification of Letters Patent.

Patented Dec. 10, 1918.

Application filed April 23, 1915. Serial No. 23,397.

To all whom it may concern:

Be it known that I, EDWARD J. BIRKETT, a citizen of the United States, and a resident of Racine, county of Racine, and State of Wisconsin, have invented certain new and useful Improvements in Excavating and Loading Machines, of which the following is a full, clear, and exact description.

The invention relates to excavating and loading machines and seeks to provide an improved apparatus for rapidly excavating and loading earth and like material into wagons, a further object of the invention being to provide an improved excavating and loading machine which can be readily transported. The invention consists of the features of improvement hereinafter set forth illustrated in the preferred form in the accompanying drawings and more particularly pointed out in the appended claims.

Figure 1 is a view in elevation of the improved apparatus. Fig. 1^a is a view in elevation of the excavating scoop. Fig. 2 is a plan view of the apparatus looking in the direction of the arrows 2—2 of Fig. 1. Fig. 2^a is a plan view of the scoop. Fig. 3 is a horizontal section of the apparatus illustrating the operating mechanism. Fig. 4 is a section on the line 4—4 of Fig. 3. Fig. 5 is a detailed section on the line 5—5 of Fig. 3. Fig. 6 is an inverted plan view of the parts shown in Fig. 5. Fig. 7 is a detailed section on the line 7—7 of Fig. 5. Fig. 8 is a partial view in side elevation with the parts of the apparatus in position for transportation. Fig. 9 is a detailed plan view with the parts shown in section on the line 9—9 of Fig. 8. Fig. 10 is a detailed section on the line 10—10 of Fig. 8. Figs. 11, 12 and 13 are detailed sections on lines 11—11, 12—12 and 13—13 respectively of Fig. 1.

For convenience in transportation, the machine is mounted upon front and rear axles 10 and 11, having wheels 12 and 13 thereon. The frame of the machine comprises side sills 14 suitably mounted upon the front and rear axles. The front wheels are preferably smaller than the rear wheels, so that they can be swung beneath the side sills. The frame of the machine above the sills is triangular in form, inclined frame bars 15 extend upwardly and rearwardly from the rear ends of the side sills and inclined frame bars 16 extend upwardly from the forward ends 55 of the side sills at a sharper angle and the

lower ends of these bars extend downwardly somewhat below the front ends of the sills. The frame bars 15 and 16 are connected at intervals by transverse bars 17, 18 and 19. Sheet metal plates 20 riveted or otherwise 60 suitably secured to the side sills and frame bars inclose the operating mechanism.

An inclined guide-way or trough 21 for the excavating scoop is provided at the upper front portion of the machine. The 65 trough is formed of sheet metal and is preferably provided with flaring side walls (see Figs. 11 and 12) and it is secured to correspondingly shaped supporting bars 22 which extend between the inclined frame bars 16, 70 which are preferably Z-shaped, as shown.

Preferably, the bottom and side walls of the trough or guide-way are provided with longitudinally extending wooden boards 24, which reduce the friction between the trough 75 and the scoop as the latter is drawn upwardly. The guide-way or trough is provided at its lower end with an adjustable section 25 (see Figs. 1, 2, 8, 12 and 13,) which, in operation, rests upon the ground, 80 as shown in Fig. 1, but which can be raised out of the way, as shown in Fig. 8, when the machine is moved from place to place. Like the main portion of the trough or guide-way, the extension 25 is formed of sheet metal 85 and is secured at its side edges to a pair of Z-bars 26 which rest upon the horizontal flanges of the fixed frame bar 16 and which are held in place thereon by angle strips 27 fixed to the bars 16 and overlapping the upper edges of the vertical flanges of the bars 26. The extension is thus adapted to slide longitudinally of the main portion of the guide-way to and from the ground. Preferably, as shown, the sheet metal body of the 90 extension 25 is provided with edge portions 28 which extend over the bars 16. The lower end or foot of the trough extension 25 is outwardly curved in longitudinal direction and is provided with lateral flaring portions 29 1 (see Figs. 1 and 2), the latter being provided with convex or rounded upper faces. The outwardly curved lower end of the extension 25 and the opposite portions 29 contact with the ground, and the latter are reinforced with castings 30 (shown in dotted lines in Fig. 1).

The extension of the guide-way or trough carries suitable means for guiding the excavating scoop and the lines connected thereto. 110

For this purpose, a pair of comparatively large drums 32 extend upwardly from the laterally projecting portions 29 thereof at opposite sides of the guide-way. These 5 drums are mounted on shafts 33, which are journaled in their lower ends in the castings 30 and at their upper ends in brackets 34. These brackets are secured to the ends of brace bars 35, which extend outwardly from 10 the bars 26.

The guiding drums 32 are thus arranged in position at a slight angle to the vertical, on opposite sides of the entrance to the guide-way. Between the upper ends of these 15 guiding drums extends a smaller transverse guiding roller 36 which is journaled at its ends in brackets 37 on the bars 35.

The excavating scoop 38 shown is of ordinary construction and the drag line 31 is 20 connected to the bail 39 thereof. Thence the drag line passes between the guiding drums 32 and beneath the guiding roller 36, thence upwardly at an incline above the guide-way to a guiding pulley 40 at the extreme upper end of 25 the machine, and thence the drag line passes downwardly over a guide pulley 41 to a winding drum 42.

The arrangement of the guiding drums 32 and the guide roller 36 is such that the 30 drag line can extend laterally from the entrance to the guide-way at a sharp angle thereto, so that a large area can be excavated without moving the machine. When the drag line extends laterally at an 35 angle to the chute, the drag rope passes around one or the other of the guiding drums 32. These drums 32, as most clearly shown in Fig. 2, form the opposite side walls of a flaring throat at the entrance of the 40 trough-shaped guide-way and serve to properly direct the scoop into the guide-way when the scoop approaches the guide-way at an angle thereto. As the scoop is thus drawn toward the entrance of the guide-way 45 its bail will strike one or the other of the guiding drums 32, but as these drums are of considerable size, the scoop will be properly deflected and will pass into the entrance of the trough-shaped guide-way. The 50 drums 32 and the roller 36 also serve to properly guide the drag line 31 as the scoop passes to and from the entrance of the guide-way. These drums and the roller also serve to guide the scoop return line 43 (herein 55 after described), as the scoop passes up and down the inclined guide-way. To prevent displacement of the lines, the ends of the guide roller 36 and the upper ends of the drums are provided with flaring flanges, as 60 shown. For this purpose, also, the lower ends are arranged within recesses (as shown in dotted lines in Fig. 1) in the offset portions 29 of the trough extension.

The return line 43 is connected to the 65 rear end of the excavating scoop and ex-

tends therefrom over a guide pulley 44 that is carried by an anchor 45 and can be fixed in any desired position within the range of the machine. From the anchor pulley 44 the return line passes upwardly over a guide 70 pulley 46 at the upper portion of the machine and thence downwardly to a winding drum 47.

The guide pulley 40 is located at the extreme upper portion of the machine and its 75 inner periphery is substantially in line with the center of the guide-way, and the guide pulleys 41 and 46 and the winding drums 42 and 47 are located at one side of the machine. Preferably, as shown, these guide 80 pulleys and winding drums are duplicated at opposite sides of the machine, as most clearly shown in Fig. 2, so that the draft and return lines for the scoop may be duplicated and the machine adapted to operate 85 with two scoops.

The guide pulleys 40, 41 and 46 are necessarily arranged at a considerable height and for convenience in transportation are preferably mounted on an adjustable frame 90 so that they can be lowered out of the way when the machine is moved from place to place. This frame comprises a pair of inclined side bars 48 having upper converging end portions connected by a member 49 95 to which the guide pulleys 40 are swiveled. The guide pulleys 41 are fixed to the bars 48 as shown in Fig. 2. The guide pulleys 46 are swiveled to short pieces 51 which project laterally from the lower ends of 100 the bars 48. The extreme lower ends of the frame bars 48 slidably engage the outward flanges of the fixed frame bars 16. The upper ends of the frame bars 48 are pivotally connected to the upper ends of a pair 105 of brace bars 52. The lower ends of the latter are pivotally connected to the upper ends of the fixed frame bars 15. Brace rods 53 (see Figs. 1 and 2) extend between the bars 52 and a pair of hook-shaped pieces 54 110 that are fixed to the extreme upper end of the guiding trough. The rods 53 are detachably bolted to the links 52 and can be disconnected so that the frame which carries the guide pulleys can be lowered, as 115 shown in Fig. 8. When this frame is lowered, the bars or links 52 swing downwardly and forwardly upon pivots between their lower ends and the frame bars 15.

This frame is raised from lowered position by a pair of ropes 55, which are connected to the lower side portions thereof and extend upwardly over a pair of guide pulleys 56 at the upper side portions of the guide-way, thence the ropes pass downwardly to a pair of small winding cones 57. By this means, the upper extension for supporting the guiding pulleys can be raised to the operative position shown in Fig. 1 and then fixed in this position by securing the brace 120

rods 53 to the bars or links 52. When the upper extension is thus raised, the ropes 55 are removed from the small winding cones 57.

5 The lower trough extension is adapted to be raised from its operative position shown in Fig. 1 to its inoperative position shown in Fig. 8 by a cable 58 fixed to a bracket 59 on its lower face and extending upwardly 10 therefrom over a guide pulley 60 (see Figs. 1 and 8) to a winding drum 61 (see Figs. 3 and 6). This drum is loosely mounted on a shaft 62, and is adapted to be connected thereto by a sliding jaw clutch 63. At one 15 end, the drum is provided with a ratchet wheel 64 which is arranged to be engaged by a spring-held pawl 65, so that the trough extension can be held in raised position against the action of gravity when the 20 clutch member 63 is in disengaged position. By shifting the pawl 65 against the tension of its spring 66 out of engagement with the ratchet 64, the trough extension can be readily lowered to its operative position shown 25 in Fig. 1.

The drag line 31 and winding drum 42 serve to effect the forward movement of the excavating scoop 38. When the scoop is filled, the drag line also draws the scoop 30 to the lower end of and up the guide-way of the trough. When the scoop reaches the upper end of the guide-way, its forward edge will strike the hooks 54, and the continued forward pull of the drag line upon 35 the scoop bail 39 will tilt the latter, as shown in dotted lines in Fig. 1, and hence discharge the contents of the scoop.

To check this tilting movement of the scoop, a U-shaped bail 67 is pivotally 40 mounted upon the frame bars 48 and springs 68 extend between the arms of this bail and the lower ends of the frame bars 48. Stops 69 on the frame bars prevent the bail from swinging forwardly from the 45 position shown in full lines in Fig. 1, but the bail can swing rearwardly against the tension of the spring 68 until arrested by a pair of stop bars 70 that project outwardly from the bars 48 (see Figs. 1 and 2). As 50 the scoop is tilted, the handle bars 38' thereon strike against the upper horizontal portion of the bail and the further movement of the scoop is resisted by the spring 68, and the scoop is finally arrested in the 55 dotted position shown in Fig. 1 when the bail 67 strikes the stop bars 70.

If desired, the scoop can dump its load directly into a cart placed beneath its dumping position, but preferably the load is 60 dumped into a receptacle large enough to contain a wagon-load, and means are provided for dumping the receptacle to quickly discharge its contents into a cart, so that practically no time is lost in unloading the 65 scoops and loading the carts.

For this purpose, a receptacle 71 is mounted at the upper rear portion of the machine immediately below the dumping position of the scoop. This receptacle comprises side walls and a flat bottom wall that 70 is curved upwardly at its rear end. This receptacle is provided at the central portions of its bottom wall with trunnions 72 which are journaled in brackets fixed to the rear frame bars 15. The rear edges of the side 75 walls are concentric with the trunnions 72 and are provided with curved flanged bars 73. The receptacle is normally held in the position shown in Fig. 1, with its bottom wall horizontal and with its rear end adjacent a curved guide plate 74 fixed to the frame of the machine beneath the upper end of the guide-way. Side plates 75 at the upper side portions of the machine also overlap the rear end of the receptacle when 80 it is in the normal position. The rear end of the receptacle is open, and to prevent the escape of material therefrom, when it is in normal position (shown in full lines in Figs. 1 and 8), a U-shaped shield 76 projects rearwardly from the frame bars 15 and covers the open rear end of the receptacle. As 85 stated, the receptacle is adapted to contain about a wagon-load of material and is held at such a height at the upper rear portion of 90 the machine that the wagon can be readily placed behind the machine and beneath the receptacle and loaded by shifting the receptacle from normal position to its dumping position, with its bottom wall downwardly and rearwardly inclined and its rear open end below the shield 76, as shown in 95 dotted lines in Fig. 1.

The parts of the machine are operated by a suitable motor arranged in the machine 105 casing below the guide-way. In the form shown, an explosive engine 77 is suitably mounted within the machine and the operating mechanism is driven from the engine shaft 78. This operating mechanism comprises the shaft 62 (already referred to) and shafts 79, 80 and 81 (see Figs. 1, 3 and 5), such shafts being journaled in suitable bearings mounted upon horizontal frame bars 17. The main power shaft 79 is provided with two sprocket wheels 82 which are connected by chains 82' to a pair of sprocket wheels 83 and 83' on the engine shaft 78. The sprocket wheels 82 are loose on the shaft 79 and adapted to be connected 110 by a suitable clutch mechanism. In the form shown, this clutch mechanism comprises a hub portion 84 which is keyed to the shaft and which is provided with two sets of toggle arms 85 and friction shoes 85', 115 the latter being arranged to coöperate with internal friction surfaces formed upon the sprocket wheels 82. A clutch shifter 86 is pivoted at 86' on a bracket 87, and is arranged to shift the clutch member to connect 120

125 130

either one of the sprocket wheels 82 to the shaft 79. Inasmuch as the companion sprocket wheels 83 and 83' on the engine shaft are different sizes, the main power shaft can thus be driven at different speeds, in accordance with the consistency of the material acted upon. In the central position of the clutch member 84, neither one of the sprocket wheels will be connected to the shaft 79 so that the mechanism is then disconnected from the motor. The forward end of the clutch shifter 86 is provided with a rod 88 which extends outwardly through the side wall of the machine casing, so that the clutch shifter may be readily manipulated.

The shaft 79 is provided at one end with a pinion 89, which meshes with the gear 90 on the shaft 62, so that the latter is continuously rotated when the machine is in operation. The drag line drums 42 are loosely mounted upon the outer projecting ends of this shaft and are adapted to be connected thereto by a pair of jaw clutches 91 which are feather-keyed to the shaft. Preferably, as shown, yokes 92 project outwardly from the bars 17 and are provided with bearings for sustaining the outer ends of the shaft 62. A pair of levers 93 for shifting the clutches 91 are pivotally mounted on the yokes 92 and these levers are connected by a transverse rod 94 which extends through the machine casing and the parts are so connected that when one clutch is engaged, the other must be disengaged, and when one of the winding drums is connected to the shaft 62 to wind up this drag line, the other drum, which is connected to the drag line of the second scoop, is necessarily disengaged from the operating mechanism.

The return line drums 47 can be rotated faster than the drag line drums and are mounted directly upon the main power shaft 79 and are adapted to be connected thereto by a pair of friction clutches 95. Guard brackets 96 fixed to the frame bar 17 and to the yokes 92, surround the winding drums 47 and levers 97 are pivotally mounted thereon for shifting the clutches 95. These levers are connected by a transverse rod 98 so that only one of the return line drums can be thrown into operation at any one time. By the mechanism described, the two scoops can be alternately operated. When one of the drag line drums 42 is in operation to draw its scoop forwardly toward the machine, the return line drum 47 of the other scoop is in operation to move it away from the machine.

The main power shaft is provided with a pinion 99 (see Figs. 5 and 6) which meshes with a gear 100 that is loosely mounted on the shaft 80. This shaft is provided with a gear 101 which meshes with a gear 102 on the shaft 81. A pair of crank arms 103

(see Figs. 1 and 2) are fixed to the ends of the shaft 81 and are connected by links 104 to the forward end of the dumping receptacle.

An arm 105 (see Figs. 5 and 6) is keyed to the shaft 80 and is provided at its end with pivoted holding and operating dogs 106 and 107. The holding dog 106 is pressed by a spring 108 and normally engages a fixed toothed plate 109, so that the shafts 80 and 81 and the parts connected thereto, including the receptacle 71, are held stationary in normal position.

The toothed plate 109 is fixed to a depending lug 110 on a bracket 111. This bracket is mounted on the shaft 81 between a pair of collars 112 thereon and the bracket is held against movement by a brace rod 113 extending between its upper end and a transverse frame bar 114, which, as shown in Fig. 1, is fixed to the frame bars 15. A short rock shaft 115 journaled in the upper end of the bracket 111 is provided with an integral depending crank arm 116 and with a depending supporting arm 117. The latter is provided with a socket for a stop bolt 118. A spring 119 within the socket tends to move the stop bolt downwardly, this downward movement being limited by nuts 120 threaded on the upper end of the stop bolt. The stop bolt cooperates with a lug 121 which is formed on the clutch dog 107. A tail 122 on this dog is engaged by a spring 123. This spring holds the lug 121 against the stop bolt 118, and, when the latter is shifted out of engagement with the lug, the spring will move the clutch dog 107 into engagement with internal teeth 124 formed upon the rim of the gear 100.

A spring 127 is interposed between the bracket 111 and holder 117, and this spring holds the stop bolt 118 in the normal position shown.

A shifter rod 125 is connected to the crank arm 116 so that the shaft 115 can be rocked to shift the stop bolt 118 against the tension of the spring 127, out of the path of movement of the lug 121. This shifter rod is connected to a crank arm 126 on the inner end of a rock shaft 128. Shaft 128 is journaled upon a bracket 129 that is fixed to one of the cross pieces 22. Shaft 128 projects outwardly through the side of the machine and has a handle 130 on its outer end by which it may be oscillated and shifted longitudinally. By oscillating the handle 130, the stop bolt 118 can be disengaged from the lug 121 so that the clutch dog 107 will engage the tooth 124 of the gear 100. Shafts 80 and 81 will then be rotated to oscillate the receptacle and dump its load. The spring 127 returns the stop bolt to normal position, as shown, so that at the end of one revolution of the shaft 80, lug 121 will engage the stop bolt and the

clutch dog 107 will be disengaged from the tooth of the gear 100. At the same time, the stop dog 106 will engage the toothed member 109 and hold the shaft 80 and parts connected thereto stationary. In this way, a single revolution will be imparted to the shaft 80 and the clutch dog will then be automatically disengaged. The gear 102 on the shaft 81 is twice as large as its coöperating gear 101 on the shaft 80, so that a half-revolution is imparted to the shaft 81 and the receptacle will be arrested in the dumping position shown in dotted lines in Fig. 1. By again throwing this clutch mechanism into operation, another half-revolution can be imparted to the shaft 81 to return the receptacle 71 to normal position.

In addition to the crank arm 126, the rock shaft 128 is provided with a shifter 131 for the clutch 63. This shifter is loosely mounted on the shaft so that it does not interfere with its oscillating movement, but is held against relative longitudinal movement by a collar 132 which is fixed to the shaft. By moving the shaft 128 longitudinally, the jaw clutch 63 can be thrown into and out of operation and thereby coöperate with the drum 61 to wind up the cable 58. Shaft 128 is also provided with an arm 133 which is arranged to coöperate with a projecting lug 134 on the side of the pawl 65. The rod 125 is shifted to throw the receptacle dumping mechanism into operation by oscillating the rock shaft 128 in one direction. This rod has a lost motion connection with the crank arm 116, so that the shaft can be oscillated in the opposite direction and when so oscillated it disengages the pawl 65 from the ratchet 64 so that the rope 58 can be unwound and the lower trough extension lowered. Shaft 128 thus serves, when oscillated in one direction, to control the receptacle dumping mechanism, when oscillated in another direction to release the pawl 65, and when shifted axially it serves to throw the clutch 63 into and out of operation.

During operation, two excavating scoops can be employed, the movement of the scoops being controlled by the clutch shifting levers 93 and 97. The material excavated by the scoop is drawn up and dumped into the receptacle 71. From thence it can be readily dumped into wagons or carts, the receptacle dumping mechanism being controlled by the rock shaft 128. The drag and return lines of the scoops can extend laterally at an angle to the machine, so that a large area can be covered without moving the machine. The lower extension of the guide-way can be readily raised and the upper extension which carries the guide pulleys can be readily lowered for convenience in transportation.

It is obvious that numerous changes may

be made in the details set forth, without departure from the essentials of the invention.

I claim as my invention:

1. In an excavating machine, the combination with a scoop and drag line therefor, of a portable frame having an inclined trough-shaped guide-way for said scoop, a guide pulley and a winding drum for said drag line mounted on said frame, and a trough-shaped extension at the lower end of said guideway adjustable to and from the ground, said extension having a foot outwardly curved in longitudinal direction and adapted to engage the ground, substantially as described. 80

2. In an excavating machine, the combination with a scoop and a drag line therefor, of a portable frame having an inclined guide-way for said scoop, a guide pulley and winding drum for said drag line mounted on said frame, and an extension mounted upon the lower end of said guide-way and adjustable longitudinally thereof to and from the ground, substantially as described. 85

3. In an excavating machine, the combination with a scoop and a drag line therefor, of a portable frame having an inclined trough-shaped guide-way for the scoop, a guide pulley and a winding drum for said drag line mounted on said frame, a trough-shaped extension at the lower end of said guide-way adjustable to and from the ground, said extension having a foot outwardly curved in longitudinal direction and provided with lateral extensions adapted to contact with the ground and upright guiding drums mounted upon the laterally projecting portions of said foot and forming the opposite side walls of a flaring throat at the lower end of said extension, substantially as described. 100 105

4. In an excavating machine, the combination with a scoop and drag line therefor, of a portable frame having an inclined guide-way for said scoop, a guide pulley and a winding drum for said drag line mounted on said frame, an extension at the lower end of said guide-way adjustable to and from the ground, and guiding devices for the scoop and drag line mounted on said extension, substantially as described. 110 115

5. In an excavating and loading machine, the combination with a scoop and drag line therefor, of a portable frame having an inclined guide-way for the scoop, a winding drum for the drag line on said frame, an adjustable extension frame at the upper end of said guideway, and guide pulleys for said drag line mounted on said extension, substantially as described. 120 125

6. In an excavating and loading machine, the combination with a scoop and drag line therefor, of a portable frame having an inclined guide-way for the scoop, a winding drum for the drag line on said frame, an ad- 130

justable extension frame at the upper end of said guide-way, guide pulleys for said drag line mounted on said extension, and mechanism for raising said extension, substantially 5 as described.

7. In an excavating and loading machine, the combination with a scoop, and drag and return lines therefor, of a portable frame having an inclined guide-way for the scoop, 10 winding drums on said frame for said drag and return lines, an extension frame adjustably mounted at the upper end of said guide-way and guide pulleys for said drag and return lines mounted on said extension 15 frame, substantially as described.

8. In an excavating and loading machine, the combination with a scoop, and drag and return lines therefor, of a portable frame having an inclined guide-way for the scoop, 20 winding drums on said frame for said drag and return lines, an extension frame adjustably mounted at the upper end of said guide-way, guide pulleys for said drag and return lines mounted on said extension, a 25 scoop-guiding extension at the lower end of said guide-way adjustable to and from the ground, and means for raising and lowering said extensions, substantially as described.

9. In an excavating and loading machine, 30 the combination with a scoop, and drag and return lines therefor, of a portable frame having an inclined guide-way for the scoop, winding drums on said frame for said drag and return lines, an extension frame adjustably mounted at the upper end of said guide-way, guide pulleys for said drag and return lines mounted on said extension, a scoop-guiding extension at the lower end of said guide-way adjustable to and from the 35 ground, adjusting ropes for said extensions, winding drums for said ropes, a motor on said frame, and means actuated thereby for operating said several winding drums, substantially as described.

45 10. In an excavating machine, the combination of a frame having an inclined scoop guide-way thereon, scoop dumping means at the upper end of said guide-way, pairs of drag and return line guide pulleys at the 50 upper end of said guide-way, a pair of drag line drums, a pair of return line drums, driving mechanism for said drums, connect-

ed clutches for alternately throwing said drag line drums into and out of operation, and connected clutches for alternately 55 throwing said return line drums into and out of operation, substantially as described.

11. In an excavating and loading machine, the combination with a scoop and drag and return lines therefor, of a portable wheeled 60 frame having an inclined scoop guide-way, guiding pulleys and winding drums for said drag and return lines mounted on said frame, means at the upper end of said guide-way for dumping the scoop, a tilting receptacle mounted at the upper portion and at the rear end of said frame and beneath the upper end of said guide-way, and a common motor on said frame for operating said winding drums and for tilting said receptacle 65 to dump the same, substantially as described.

12. In an excavating and loading machine, the combination of a frame having an inclined scoop guide-way thereon, scoop 70 dumping means at the upper end of said guide-way, a tilting receptacle open at one end mounted on said frame below the upper end of said guide-way, a fixed shield normally closing the open end of said receptacle, and mechanism for tilting said receptacle, substantially as described.

13. In an excavating and loading machine, the combination of a frame having an inclined scoop guide-way thereon, a receptacle 75 mounted on said frame below the upper end of said guide-way, mechanism for moving said receptacle between its normal and dumping positions and for holding the same in either of said positions, and an automatically disengaged clutch for throwing said mechanism into operation, substantially as described.

14. In an excavating and loading machine, the combination of a frame having an inclined scoop guide-way thereon, a tilting receptacle mounted on said frame below the upper end of said guide-way, an operating shaft having crank arms thereon, links connecting said arms to said receptacle, and means for intermittently actuating said shaft, substantially as described.

EDWARD J. BIRKETT.
